UNITED STATES PATENT OFFICE.

EDWARD MARCILLE, OF DECATUR, ILLINOIS.

BOX-TOOL.

SPECIFICATION forming part of Letters Patent No. 729,372, dated May 26, 1903.

Application filed February 27, 1902. Serial No. 95,991. (No model.)

To all whom it may concern:

Be it known that I, EDWARD MARCILLE, of the city of Decatur, county of Macon, and State of Illinois, have invented certain new and useful Improvements in Box-Tools, of which the following is a specification.

The object of this invention is to provide means for accurately and rapidly turning articles having either parallel sides, tapered sides, or partly straight and partly tapered sides.

The invention is exemplified in the structure hereinafter described, and it is defined in the appended claims.

In the drawings forming part of this specification, Figure 1 is a side elevation of the tool. Fig. 2 is an end elevation of the tool. Fig. 3 is a plan of the body member of the tool. Fig. 4 is a side elevation of one of the adjustable work-guides. Fig. 5 is an end elevation of the work-guide. Fig. 6 is a detail of one of the bolts used to adjust the work-guides. Fig. 7 is an elevation of the inner surface of the tool-post. Fig. 8 is a section through the tool-post on line X in Fig. 7.

The body member of the tool comprises a plate 1; an extension 2, rising from one end of the plate, and a stem 3, by which the tool is held in a lathe-chuck or other support. The tool-post 12 sits on plate 1 at one side of the axis of the tool, and it is held in place by bolts 16 and 17, as shown in Fig. 7. Bolt 16 extends through hole 22, (shown in Fig. 3,) and bolt 17 extends through the slot 23, which is in the form of an arc drawn with hole 22 for a center. The outer edge of the slot is in line with the outer edge of the hole, the inner side of the slot is extended inward past the inner side of the hole, and the bolt-holes in the tool-post are in a line parallel with the face of the post, so when bolt 17 rests against the outer edge of slot 23 the tool-post is parallel with the axis of the shaft 3 and with the motion of the work into the box-tool. When bolt 17 is loosened, moved inward in the slot, and retightened, the tool-post forms an angle with the motion of the work or with the axis of the box-tool that is proportionate to the extent of the inward shift of bolt 17 in slot 23. The tool-post is slotted from inside to outside in a plane parallel with plate 1, as shown in Figs. 7 and 8, and tools, as 13 and

14, may be inserted through the slot and held in place by clamp-screws 15. Bolts 8 extend through sleeves 6, and they have shoulders 8^a on their inner ends, against which the sleeves are clamped by nuts 9. Guide-bars 19 are pivotally connected with bolts 8, and renewable bearing-strips 20 are held in grooves in bars 19.

The face of the tool-post is circularly recessed, as shown at 21 in Fig. 7, and the side of tool 13 extends into the recess and is sharpened to face off the work when such facing is desired.

A guide member 5 rises from plate 1 on the side thereof opposite tool-post 12, and it curves over the center of plate 1 at its upper end. A groove 4 is formed in a rib on plate 1 and the guide member has a rib 5^a on its lower inner edge, that extends into the groove 4. Bolts 18 extend through slots in plate 1 and screw into the guide member, and these bolts aid the rib 5^a to resist the stress of the work against the work-guides. A post 10 is secured to plate 1 in the rear of the vertical part of the guide member 5, and a screw 11 extends through the post and into the guide member and provides means for adjusting the guides lengthwise of the body.

A pair of externally-threaded sleeves 6 is screwed vertically through the horizontal extension of the guide member, and another pair of sleeves is screwed through the vertical extension of member 5. Finger-wheels 7 on sleeves 6 provide means for screwing the sleeves in and out. Bolts 8 extend through sleeves 6, and they have shoulders 8^a on their inner ends, against which the sleeves are clamped by nuts 9. Guide-bars 19 are pivotally connected with bolts 8 and renewable bearing-strips 20 are held in grooves in bars 19.

The face of the tool-post is circularly recessed, as shown at 21 in Fig. 7, and the side of tool 13 extends into the recess and is sharpened to face off the work when such facing is desired.

The box-tool may be held against rotation and moved to and from the work while the work is rotated, or it may be made to rotate while the work is fed into it.

The tools 13 and 14 and the guide-bars 20 are adjusted to conform to a sample-finished article that it is desired to reproduce in

quantities, and when the adjustment is correctly made one article after another is shaped with rapidity and precision.

When the article to be turned has straight 5 or parallel sides, the tools and guides are set somewhat as shown in the drawings, the question of diameters alone being considered; but when the article is tapered the tools and guides are set on inclines corresponding to 10 the taper of the work. When the work is partly tapered and partly straight, the tool 13 is set at the proper angle to produce the required taper and the other tool is set straight.

15 In adjusting the tools and guides a finished sample is put in place in the box-tool, the tool-post and the tools therein are adjusted to conform to the outline of the sample, the nuts 9 are loosened, the guides are lined up 20 against the work, the sleeves are screwed inward until their inner ends bear against the shoulders 8^a of the bolts, and the nuts 9 are retightened to clamp the sleeves against rotary motion. After the tools 13 and 14 are 25 properly adjusted the screws 15 are tightened to make the adjustment secure.

The stress of the work is downward on the tool-post, but it is upward on the guides and special provision is needed to overcome the 30 stress on bolts 18. The rib 5^a acting in groove 4 resists the upward stress on the guide member to the full extent of the strength of the metal in the rib, and it also provides for lengthwise adjustment of the guide member on the body- 35 plate.

The front ends of the guides must be slightly in the rear of the front edge of the tool 13, so that the tool will cut a bearing for the guides. The advance of the tool should not be more 40 than is actually needed to make the necessary bearing-surface, and so it is very desirable to have the guide member adjustable.

The sleeves 6 and the bolts therein move in 45 and out in parallel lines, and to permit the guide-bars to assume inclined positions one bolt 8 of each pair is slotted at its pivot to permit the movement of the pivot-pin that the obliquity of the guide-bar requires. (See 8^b in Fig. 6.)

I claim—

1. In a box-tool, the combination of a body-plate, a guide member secured to a side of the plate and extended around the axis of the work, an elongated tool-holder on the opposite side of the plate, pivoted at one end to 55 the plate, and a clamp-bolt for securing the swinging end of the tool-holder to the plate in various positions, whereby the tool in the holder may be set parallel with the axis of the work or at various angles with relation thereto. 60

2. In a box-tool, the combination of a body-plate, an elongated tool-holder hinged at one end to one side of the body-plate a clamp-bolt to secure the swinging end of the tool-holder to the plate in various positions, a guide 65 member longitudinally slideable on the opposite side of the plate, and guide-bars adjustable in the guide member to and from the work.

3. In a box-tool, the combination of a body comprising a plate, a lateral extension of the 70 plate and a stem on the extension, a tool-post angularly adjustable on one side of the plate, a grooved rib rising on the opposite side of the plate, a guide member having a rib engaging the groove of the plate, such guide being 75 extended partly around the axis of the work, and guide-bars adjustable in the guide member to and from the work.

4. In a box-tool, the combination of a body-plate, a tool-post angularly adjustable on one 80 side of the plate, a guide member attached to the opposite side of the plate and extended partly around the axis of the work, externally-threaded sleeves screwed into the guide member and arranged in pairs disposed length- 85 wise of the tool, bolts in the sleeves having shoulders bearing against the inner ends of the sleeves, nuts on the outer ends of the bolts to clamp the sleeves between the nuts and the shoulders of the bolts, and guide-bars 90 pivotally connected with the inner ends of the bolts.

In testimony whereof I sign my name in the presence of two subscribing witnesses.

EDWARD MARCILLE.
